[57] CLAIM

The ornamental design for a combined baby pacifier and cover, as shown and described.

DESCRIPTION

FIG. 1 is a left front side perspective view of a combined baby pacifier and cover, showing my new design, with the cover attached;

FIG. 2 is a right rear side perspective view thereof;

FIG. 3 is a front elevational view thereof;

FIG. 4 is a bottom plan view thereof, with the top plan view being a mirror image thereof;

FIG. 5 is a right side elevational view thereof;

FIG. 6 is an exploded right front side perspective view thereof, with the cover removed;

FIG. 7 is an exploded left rear side perspective view thereof; and,

FIG. 8 is a front elevational view thereof.
